UNITED STATES PATENT OFFICE.

ANDREW G. WASS, OF MINNEAPOLIS, MINNESOTA.

CASEMENT-WINDOW LOCK AND JOINT-STRIP.

1,216,524.

Specification of Letters Patent. Patented Feb. 20, 1917.

Application filed March 20, 1916. Serial No. 85,230.

To all whom it may concern:

Be it known that I, ANDREW G. WASS, a citizen of the United States, residing at Minneapolis, in the county of Hennepin and State of Minnesota, have invented certain new and useful Improvements in Casement-Window Locks and Joint-Strips; and I do hereby declare the following to be a full, clear, and exact description of the invention, such as will enable others skilled in the art to which it appertains to make and use the same.

My invention has for its object to provide an extremely simple and highly efficient combined lock and joint strip for casement windows; and, to such ends, generally stated, the invention consists of the novel devices and combinations of devices hereinafter described and defined in the claim.

Locks for casement windows should be capable of securing the same, not only in closed positions but also in various different more or less opened positions. Efficient locks for this purpose, as hitherto provided, have been very complicated and expensive. Furthermore, it is a well known fact that it is very difficult to make tight joint strips, such as will exclude water and air, between the lower edge of the sash and the window-stool.

My invention provides an extremely simple and highly efficient combined lock and joint strip. The preferred form of this improved device is illustrated in the accompanying drawings, wherein like characters indicate like parts throughout the several views.

Referring to the drawings,

Figure 1 is a fragmentary view in side elevation showing my invention as applied to a casement window, the said parts being viewed from the inside of a building;

Fig. 2 is a horizontal section taken on the line $x^2 x^2$ of Fig. 1;

Fig. 3 is a vertical section taken on the line $x^3 x^3$ of Fig. 1;

Fig. 4 is a horizontal section taken on the line $x^4 x^4$ of Fig. 3; and

Fig. 5 is an edge elevation showing the lower portion of the casement sash.

The numeral 1 indicates the framework of a casement window, the same having, in the outer portion of its stool 2, a rabbet 3 that affords a stop shoulder that is preferably faced with a metal strip 4 set slightly oblique in respect to vertically.

The casement sash 5, as is usual, is hung on hinges 6 for horizontal swinging movement and it is arranged to seat against upright stop strips 7 on the sides of the frame 1. The lower portion of this sash is formed with a deep narrow groove 8 that extends from side to side of the sash and opens at the bottom of the sash. A flat metal blade 9 that affords both a lock and a joint strip and extends from one side to the other of said sash, works through the lower portion of the slot 8 and directly between metal guide strips 10 that are countersunk into the bottom of the sash and extended slightly up the side edges of the sash. At its central portion, this lock strip 9 is rigidly secured to a vertically movable plate 12 that has dove-tailed engagement with a metallic guide channel 13 set into the sash and rigidly secured thereto by screws or other suitable devices. The plate 12 holds the lock strip 9 always horizontal but free for vertical movement.

The numeral 14 indicates a tumbler or stud shaft mounted to rotate in a bearing sleeve 15 set into the sash and provided, at its outer portion, with a flange that is secured to the sash by screws 16 or other suitable means. A screw 17, applied to the outer portion of the sleeve 15 and engaging an annular groove 18 in the shaft 14, holds the latter against endwise movements, but free for rotary movements. At its outer ends, the shaft 14 is provided with an operating knob 19 and, at its inner end, it is provided with an eccentric stud or crank pin 20 that engages a horizontal slot 21 in the vertically movable plate 12.

Secured in a suitable position on the stool 2, is a latch bar 22 provided, as shown, with slots or depressions 23 and 24.

With the device described, the sash can be freely swung to and from a closed position when the lock strip 9 is raised. When the sash is swung to a closed position, the strip or blade 9 may be lowered by rotation of the knob 19 and shaft 14, and when it is thus lowered against the metal faced lock shoulder 4 of the window-stool, the window will be securely locked in such closed position and a very close and tight joint will be formed between the sash and stool such as required to exclude rain and air. Furthermore, when the said combined lock and joint strip 9 is lowered, the crank pin 20 will be thrown to its lowermost or dead center posi-

tion, so that no amount of force applied to the said strip 9 will serve to raise the same. The sash is, therefore, then securely locked and made burglar-proof.

5 By opening the sash to positions in which the lock strip 9 is alined with one or the other of the notches 23-24 of the latch bar 22 and the said lock strip is then lowered into engagement with the alined notch, the 10 sash may be securely locked in any one of several open positions. The vertically movable strip or blade 9, therefore, performs several important functions, to wit: that of a joint strip, that of a lock for securing 15 the sash in a closed position, and that of a device for securing the window in different open positions.

The device, furthermore, is of such nature 20 that it may be very easily applied to casement windows already erected. Of course, it may be also applied to so-called "French" doors and to both vertically and horizontally pivoted window sashes. In fact, in this specification and in the claim, the term "case-

ment window" is used in a broad sense to 25 include all swinging window sashes or doors.

What I claim is:—

The combination with a window sash having a slot in the lower rail thereof and a transverse recess communicating with said slot, of a channel-plate guide located within the recess in said rail and having its channel opening into the slot, a combined lock and joint strip movable in said slot, a sliding plate extending from said strip and operable in the channel of said guide plate, and an operating shaft extending into the aforementioned rail and having a cam connection with the sliding plate and having, also, 30 its inner end extending through the channel 35 of said channel-plate guide and into said plate.

In testimony whereof I affix my signature in presence of two witnesses.

ANDREW G. WASS.
